UNITED STATES PATENT OFFICE.

GEORGE A. SEIB, OF ILION, NEW YORK, ASSIGNOR TO REMINGTON TYPEWRITER COMPANY, OF ILION, NEW YORK, A CORPORATION OF NEW YORK.

TYPEWRITING MACHINE.

Application filed August 21, 1922. Serial No. 583,359.

To all whom it may concern:

Be it known that I, GEORGE A. SEIB, a citizen of the United States, and resident of Ilion, in the county of Herkimer and State of New York, have invented certain new and useful Improvements in Typewriting Machines, of which the following is a specification.

My present invention relates to controlling and arresting means for the type bars of typewriting machines, and its general object is to provide new and improved mechanism of the character specified and which results in checking the speed of the type bar and in arresting it prior to the printing moment with a minimum of noise, and with the further result that it is promptly thrown away from the platen after printing contact, leaving a clear imprint.

To the above and other ends which will hereinafter appear, my invention consists in the features of construction, combinations of devices and arrangements of parts to be hereinafter described and particularly pointed out in the claims.

In carrying out my invention in the present instance I provide in connection with an escapement-actuating universal bar which is operated directly by the type bars, yieldable arresting devices which comprise a stationary stop and a co-operative stop movable by the universal bar through a train of connections, causing the two stops to co-act to substantially arrest the universal bar as each type bar nears the printing point. As the stop devices associated with the universal bar are yieldable, the type bar is checked, but is not brought to a dead stop. It continues its movement towards the platen at reduced speed, finally contacting with a separate stop or arresting device which is preferably in the form of the coiled wire stop disclosed and claimed in my co-pending application Sr. No. 571,154, filed June 27, 1922. This last named arresting device or anvil with which the type bar contacts at reduced speed, further checks the type bar but also preferably yields slightly, finally, however, arresting the type bar just prior to the instant of printing. While of course not limited to any specific points at which the devices embodying my invention become effective, I have, nevertheless, found it desirable in practice to cause the co-op-

erating stops for the universal bar to contact after the loose dog of the escapement has disengaged from the escapement wheel and when the active type is between one-eighth and one-tenth of an inch of the platen, while the type bar itself subsequently contacts directly with the wire stop or cable anvil when the active type is about .005 of an inch away from the platen. Although the stop or bumper devices associated with the universal bar may be employed without the stop or anvil that directly arrests the type bars, nevertheless I have found that highly satisfactorily results are obtained by employing the two separate stops in combination, and prefer so to employ them.

My present invention will be described in detail in connection with the accompanying drawings, wherein—

Figure 1 is a fragmentary front to rear vertical sectional view of a No. 10 Remington typewriting machine embodying the preferred form of my invention.

Figure 2 is a fragmentary horizontal sectional view taken on a plane indicated by the section line 1—1 in Figure 1 and looking downward in the direction of the arrows at said line.

Figure 3 is a fragmentary perspective view of one of the universal bar stop devices and its mounting.

Figure 4 is a perspective view of the universal bar stop device shown detached.

Figure 5 is a fragmentary view on an enlarged scale showing the relationship of the advancing type to the printing face of the platen at the moment of contact between the type bar and its stationary arresting device or anvil.

Figure 6 is a fragmentary view of a modification; and

Figure 7 is a corresponding view of another modification.

Referring first to the preferred construction illustrated in Figs. 1-5 inclusive, the main frame of the machine comprises a base 1, posts 2, and a top plate 3 above which is mounted a traveling carriage (not shown) carrying a platen 4, the step-by-step movements of the carriage being controlled by escapement devices comprising a dog-carrying rocker 5 having stationary pivots 6 and connected by a link 7 with key operated universal bar mechanism. Said mechanism

comprises a rock shaft 8 which bears at its ends on screw pivots 9 mounted on brackets 10 depending from the top plate. Rising from the rock shaft near its ends are integral arms 11 having forked or slotted upper ends, and between the arms 11 is a third upstanding arm 12 which is also integral with the rock shaft, said arm 12 having a forked upper end which receives a screw pin 13 engaged by the slotted forward end of the link 7, which thus connects the dog rocker 5 with the rock shaft 8. Said rock shaft is also connected with a universal bar frame comprising a universal bar proper 14 and arms 15 integral with and extending rearward from the universal bar between its ends, the rear end portions of the arms 15 being pivotally connected with pins or screw pivots 16 which bridge and are mounted on the forked upper ends of the arms 11, the arms 15 fitting loosely in said ends. The universal bar 14 is curved or arcuate and is adapted to be directly actuated by each and all of the set of type bars. Said universal bar is housed or seated in an arcuate groove or slotway indicated at 17 formed in the rear face of an upright type bar support or segment 18 which is mounted on the framework of the machine. Centrally the universal bar is provided with an upstanding lip 19 which carries a guide pin 20 that engages in a hole indicated at 21 in the segment 18. The construction is such that when the universal bar is moved bodily rearward its integral arms 15 will move with it, and through the pivotal connections 16 will rock the shaft 8, this rocking motion being transmitted to the arm 11 which in turn through the link or connector 7 will turn the dog rocker on its pivots 6 and actuate the escapement mechanism, as is usual in the Remington machine.

The type bars are arranged in an arc of a circle below the platen. Each type bar 22 normally rests on a pad 23 and is provided with a type head 24 carrying two types 25 and 26. A fulcrum wire 27 provides a pivot which is common to all of the type bars, said fulcrum wire being arcuate in shape and being supported on the segment 18. The heel portion of each type bar 22 is formed in rear of its pivot with a cam slot, indicated at 28, with which co-operates a pin or actuator 29 fixed to and projecting laterally from the upper end of a bell crank lever 30 which is guided in a slot, indicated at 31, formed in a cross bar or bracket 32 which extends transversely of the base frame 1 and is detachably secured to the side portions thereof. The bell cranks 30 are fulcrumed on a wire 33 that is mounted on the cross bar or bracket 32, said wire bridging the slots 31 and providing a common pivot for all of the bell cranks 30. The fulcrum wire 33 is retained in place by

a retaining plate 34 which is arranged under the cross bar 32 and is provided with fingers or lugs 35 which extend upward through a slotway in the cross bar 32 and serve to support the fulcrum wire 33 between the slots 31 in said cross bar, the retaining plate 34 being secured to said cross bar by screws 36. The short arm of each bell crank 30 is pivotally connected at 37 with a key lever 38 provided with a finger key 39, the set of key levers being pivoted on a fulcrum plate 40 in rear of the base. When one of the key levers is actuated, it operates through the described train of connections, including the bell crank 30, pin 29 and cam slot 28, to actuate its type bar 22 and swing it from its position of rest against the pad 23 upward and rearward into printing contact with the front face of the platen 4. As the type bar nears the platen the contact or engaging face 22a with which it is formed forward of its pivot 27 engages with the universal bar 14 and moves it rearward, causing said universal bar to actuate the dog rocker 5 and the other elements of the escapement mechanism in the manner described above.

In order to eliminate as far as possible the noise resulting from the impact of the type bars against the platen, means are provided to check or greatly reduce the speed of the actuated type bar as it nears the platen. In the present instance I employ for this purpose devices comprising arresting means for the universal bar, said means being adapted to yield or give slightly under the impulse of the advancing type bar so that while checking the type bar the universal bar may still move or give sufficiently to the type bar to permit it to print. The arresting means for the universal bar comprises two co-acting stop devices, one stationary and one so connected with the universal bar as to be moved thereby into contactive engagement with the stationary stop. The stationary stop is in the form of a Y-shaped bracket comprising two angularly disposed branches 41 terminating in parallel extensions 42 formed with slots 43, the branches 41 at their junction being provided with an upstanding ledge, contact or stop device proper 44. The stationary stop member 41-44 is secured to the under face of the retaining plate 34 by certain of the screws 36, said screws passing through the slots 43 and acting to adjustably clamp the stop member to a stationary part of the machine, viz, the bracket 32. The screws when loosened permit the stop member to be moved either forward or backward so as properly to locate the contact stop 44. The stop device that co-operates with the stop 44 is in the form of an arm 45, preferably trough-shaped in cross section in order to promote stiffness. Said arm is se-

cured at its upper end by headed screws 46 to an enlargement or lug 8^a preferably cast integral with the rock shaft 8 at about the middle of its rear side. The face of the lug is machined to enable the arm 45 to be closely fitted thereto and then clamped by the screws 46 so that said arm is rigid with the rock shaft. To the lower or free end of the arm 45 is secured, as by a rivet 47, 10 a pad 48 of sound deadening material, such as leather, fiber or the like. The pad is in the form of a strip which is folded and applied to the central part of the trough-shaped arm 45 between its side edge portions, the rivet passing through both folds or plies of the insulating material or pad 48 and through the central part of the arm 45 as well. The construction is such that the lower padded end of the arm 45 will 20 contact with the stop proper 44, the leather ply or fold at the front side of the arm 45 contacting directly with the rear face of the ledge or stop proper 44 when the shaft 8 is rocked during the operation of the universal bar by the type bar. The parts are so timed that the stop devices 45, 48 and 44 for the universal bar will come into contactive engagement, as shown by the dotted lines in Fig. 1, after the dog rocker 5 has 30 been rocked sufficiently to carry the usual stepping dog out of engagement with the escapement wheel. In other words, the slowing up of the universal bar as a result of the engagement of the stop devices 44 and 45, 48 does not slow up or otherwise affect the carriage feeding or escapement devices. The result of the contactive engagement of the stop devices 48 and 44 is partially to arrest the universal bar 14 as 40 well as the actuated type bar 22 which is in contactive engagement at its face 22^a with said universal bar. At the time the slowing up of the parts begins the type bar will be in the position illustrated by heavy dotted lines in Fig. 1. The further advance of the type bar to printing contact with the platen is permitted in the present instance by reason of the yield or give in the parts or train of connections extending from 50 the universal bar 14 to the point of contact between the stop pad 48 and the stationary contact 44. Of course if the parts were entirely rigid the universal bar, as well as the type bar, would be effectually arrested and brought to a dead stop as soon as such 60 contact takes place. However, the yield or give in the joints of the train and the spring of the parts or members composing the train, are sufficient to permit the completion of the printing movement of the type bar at reduced speed owing to the absorption of a considerable portion of the momentum of the type bar in overcoming the resistance of the universal bar and the universal bar arresting devices. As a result, the printing

blow of the type bar is softened and the noise largely done away with. It will be understood that I have described above only one of the methods which might be employed to cause the universal bar to check 70 the type bar without bringing it to a dead stop.

I have found in practice that if the universal bar arresting devices are employed alone to soften the blow and reduce the 75 noise of the striking type bar, the type impression is not quite so clear as when an anvil or arresting device, with which the type bar may directly contact, is also made use of, this direct arresting device for the type 80 bar serving to take out the vibrations and also to promote the speed of retraction of the type bar from the platen, these things promoting a clear sharp type impression of the type. Accordingly I prefer to employ in 85 addition to or in combination with the arresting devices 44, 48 which are disposed outside the path of the type bars as well as of the universal bar, an additional device lying in the path of the type bars and with 90 which the type bars themselves may contact directly, and I have found that a type bar arresting device or coiled wire anvil of the character disclosed in my prior application, Sr. No. 571,154 aforesaid, gives highly sat- 95 isfactory results. As illustrated in Fig. 1 herein, said type bar arresting device is in the form of a compound wound spiral wire stop 49 within which is a core 50 composed of an oppositely wound compound wire, the 100 arresting device or anvil 49, 50 being seated in an arcuate groove or depression, indicated at 51, formed in the front face of the type bar segment 18 and being retained in said seat by a plate 52 detachably secured to 105 the segment. The contact face of the anvil 49, 50 projects slightly beyond the face of the segment and is so related to the arresting devices 44, 48 that the type bar will contact with the anvil 49, 50 after the contactive 110 engagement of the stops 44, 45, but before the printing type has struck the platen. This relationship or timing of the parts is brought out clearly by the dotted lines in Fig. 1. The heavy dotted line shows the 115 position of the type bar when the arresting devices for the universal bar contactively engage, while the light dotted line shows the advanced position of the type bar when it contactively engages with the cable anvil 49, 120 50. This latter position is further illustrated by the enlarged diagrammatic view in Fig. 5, from which it is clearly apparent that the printing type although very close to the platen has not quite reached or contacted with it at the time the cable anvil comes into play. Printing contact of the 125 advancing type with the platen is permitted to some extent by reason of the yield of the elastic or resilient anvil 49, 50, the reaction 130

of the anvil adding to the speed with which the type bar is retracted after printing. Of course the employment of the yielding cable anvil as an additional arresting device 5 further results in reducing the speed of the type bar and softening the blow thereof, so that the noise resulting from its impact against the platen or the paper thereon is in a large degree eliminated as the result of 10 the combined use of the two independent stop means, one for the universal bar and one for the type bar itself.

While as stated it is preferred to employ universal bar arresting means in combination 15 with a yielding or spring anvil 49, 50, as illustrated in Fig. 1, nevertheless good results are obtainable by the employment of a different style of anvil in combination with the universal bar arresting means. Fig. 20 6 illustrates a modified construction wherein the yielding anvil of Fig. 1 is replaced by a solid anvil or arresting device, the construction otherwise being the same as the Fig. 1 construction including the universal 25 bar arresting means. As shown in Fig. 6 the type bar segment 53 may be provided with an arcuate stop or anvil 54, this anvil being solid and preferably, as is usual, cast integral with the segment and projecting 30 from the front face thereof in the form of a rib or abutment. As stated this solid anvil or stop 54 replaces the yielding anvil of the prior construction. The solid anvil is preferably set slightly to the rear of the position 35 occupied by the arresting face of the spring anvil, or in other words, the vertical plane of the striking face of 54 is closer to the vertical printing plane passing through the printing point at the front side of the platen, this 40 closer setting of course being for the reason that there is no yield in the solid anvil. As in the prior construction the anvil 54 comes into play or arrests the type bar after the speed of the type bar has been checked by 45 the universal bar and its stop arresting means.

A further modification is illustrated in Fig. 7, the type bar support or segment 55 therein shown being without any anvil or 50 arresting device for the type bar, this construction depending solely on the universal bar and its arresting means 44, 48 to check the type bar sufficiently prior to its printing contact with the platen.

Various other changes besides those described may be made without departing 55 from my present invention.

It will be observed that by my present invention I have provided a key actuated type 60 bar and a universal bar adapted to be operated when the type bar key is actuated, in combination with a stop for substantially arresting or checking the universal bar before the type bar reaches the platen, and a 65 separate stop for the type bar; that stop

means or devices are provided for substantially arresting or retarding both the universal bar and the type bar, the universal bar being arrested before the arrest of the type bar and being adapted to yield or give 70 to a certain extent after it is arrested, the type bar stop in its preferred form also being adapted to yield slightly after being engaged by the type bar; that two separate and distinct arresting means are provided for the 75 type bar one operating after the other, one of said means operating directly on the type bar without the interposition of other mechanism, and the other means having what may be called an indirect action, that is to say, the coacting stops (in the present case 48 and 44) are out of the path of the type bar but act to arrest another part or member, viz, the universal bar, which lies in the path of the type bar; that a stationary type bar stop is provided that is interposed directly in the path of the type bar, and a second stationary stop which is disposed outside of the path of movement of the type bar, in combination with a contact device or universal bar which is operated directly by the type bar, and also a train of connecting devices (comprising in the present case arms 15, arms 11, rock shaft 8, arm 45 and stop 48) which are arranged between the contact device and universal bar and said second stationary stop; that the described construction provides means for arresting the universal bar before the completion of the type stroke; that said universal bar is actuated in the present instance by the type bar itself and that its arrest takes place before the type bar completes its printing movement and contacts with the platen; and that the universal bar is actuatable directly by the type 95 bar and is associated with yielding stop devices which are adapted to co-operate before the type bar strikes directly against the anvil, the yielding stop devices operating to check the speed of the type bar before its 100 contact with the anvil.

What I claim as new and desire to secure by Letters Patent, is:—

1. In a typewriting machine, the combination of a platen, a type bar, a key for actuating said type bar, a universal bar adapted to be operated when said key is actuated, a stop for arresting said universal bar before the type bar reaches the platen, and a separate anvil stop device directly 115 contactive with the type bar.

2. In a typewriting machine, the combination of a platen, a type bar, a key for actuating said type bar, a universal bar adapted to be operated when said key is actuated, 120 stop devices for arresting the universal bar, and an anvil stop for the type bar, the universal bar being arrested by its stops before the arrest of the type bar by the anvil stop.

3. In a typewriting machine, the combina- 125

- tion of a platen, a type bar, a key for actuating said type bar, a universal bar adapted to be operated when said key is actuated, stop devices for arresting the universal bar, and 5 an anvil stop device for the type bar, the universal bar being arrested before the arrest of the type bar but being adapted to yield or give after it is arrested and the anvil stop device for the type bar being adapted 10 to yield slightly after being engaged by the type bar.
4. In a typewriting machine, the combination of a platen, a key operated type bar, escapement devices including a universal bar 15 directly operated by said type bar, a stop for arresting said universal bar before the type bar reaches the platen, and a separate anvil device directly engageable by the type bar.
- 20 5. In a typewriting machine, the combination of a platen, a key operated type bar, and two separate arresting means for said type bar, said means comprising an anvil directly co-operative with the type bar.
- 25 6. In a typewriting machine, the combination of a platen, a key operated type bar, and two distinct arresting means for said type bar, said means operating one after the other and comprising an anvil with which 30 the type bar directly engages.
7. In a typewriting machine, the combination of a platen, a key operated type bar, and two distinct yieldable arresting means for said type bar, said arresting means comprising an anvil with which said type bar 35 directly engages.
8. In a typewriting machine, the combination of a platen, a key operated type bar, a stationary type bar anvil interposed directly 40 in the path of the type bar, a second stationary type bar stop disposed outside of the path of movement of the type bar, a contact device operative directly by the type bar, and a train of devices arranged between said 45 contact device and said second stop.
9. In a typewriting machine, the combination of a platen, a curved universal bar, a key actuated type bar effective to operate said universal bar, means including a rock 50 shaft for supporting said universal bar, a stop arm projecting from said rock shaft, and a stationary bracket having a contact face adapted for co-operation with said stop arm, said bracket being adjustable to vary 55 the position of said contact face.
10. In a typewriting machine, the combination of a platen, a key actuated type bar, a curved universal bar operative thereby, means including a rock shaft for supporting 60 said universal bar, a stop arm rigid with said rock shaft and provided with a pad of sound deadening material, and a stationary stop with which the padded portion of said stop arm is adapted to contact to arrest said 65 universal bar.
11. In a typewriting machine, the combination of a platen, a key actuated type bar, a curved universal bar operative thereby, means including a rock shaft for supporting said universal bar, a stop arm rigid 70 with said rock shaft and provided with a pad of sound deadening material, and a Y-shaped bracket slotted to accommodate screws whereby it is adjustably secured to a stationary part, said bracket being provided with a stop face engageable by said pad to arrest said rock shaft and said universal bar. 75
12. In a typewriting machine, the combination of a platen, a type bar, a wire anvil therefor, a universal bar actuatable by said type bar and yielding stop devices associated with said universal bar; said stop devices being adapted to co-operate before the type bar strikes the wire anvil. 80
13. In a typewriting machine, the combination of a platen; a key actuated type bar; a segment on which said type bar is mounted, a stationary stop disposed outside the path of movement of said type bar; a co-operative stop; a train of operative connections whereby said type bar is effective to move said co-operative stop into engagement with said stationary stop, said train including a curved member engageable directly by 85 the type bars and provided with parallel arms, and a rock shaft to which said co-operative stop is fixed, said rock shaft being connected to said arms; and a wire stop mounted on said segment in the path of 90 movement of said type bar, said wire stop comprising two spirals of wire compound wound and arranged one inside the other. 95
14. In a typewriting machine, the combination of a platen, a key actuated type bar, a segment on which said type bar is mounted, a stationary stop disposed outside the path of movement of said type bar, a co-operative stop, a curved universal bar engageable directly by the type bars and provided with 100 parallel arms, a rock shaft to which said co-operative stop is fixed, said rock shaft being connected to said arms; and a wire stop mounted on said segment in the path of 105 movement of said type bar, said wire stop comprising two spirals of wire compound wound and arranged one inside the other. 110
15. In a typewriting machine, the combination of a platen; a key actuated type bar; a segment on which said type bar is 115 mounted; a stationary stop disposed outside the path of movement of said type bar; a co-operative stop; a train of operative connections including a curved universal bar engageable directly by the type bars, and a 120 rock shaft to which said co-operative stop is fixed, said rock shaft being connected to said universal bar; and a wire stop mounted on said segment in the path of movement of 125 said type bar.

⑥

16. In a typewriting machine, the combination of a platen; a key actuated type bar; a stationary stop disposed outside the path of movement of said type bar; a co-operative stop; a train of operative connections whereby said type bar is effective to move said co-operative stop into engagement with said stationary stop, said train including a curved member engageable directly by 5 the type bars and provided with parallel 10 arms, and a rock shaft connected to said

arms and to which said co-operative stop is fixed; and an anvil arranged to intercept said type bar after said stops have engaged.

Signed at Ilion, in the county of Herkimer 15 and State of New York, this 17th day of August, A. D. 1922.
